UNITED STATES PATENT OFFICE

2,425,142

MEASURING AND DISPENSING CONTAINER

John T. Brubaker, Luray, Va.

Application April 15, 1944, Serial No. 531,165

16 Claims. (Cl. 222—455)

1

This invention relates to a container, receptacle or the like adapted to dispense various fluent materials, particularly sugar, in such manner as will avoid waste, and in a measured or predetermined quantity through movement of the container from an upright to a tilted position.

I especially aim to provide a simple and inexpensive construction capable of expeditious manufacture and having parts capable of ready disassembly to facilitate cleaning so that the structure may be maintained in a sanitary condition at all times.

An important object is to provide a construction which may be made so as not to wholly or partially refill during a dispensing operation.

Further, an aim is to provide various constructions to accomplish the ends stated, all of which have a novel section or part positioned in whole or in part by a cover or closure.

The more specific objects and advantages will become apparent from a consideration of the description following, taken in connection with the different specific forms.

In said drawings:

Figure 1 is a central vertical section through one form of the container, carrying out the invention;

Figure 2 is a horizontal section taken on the line 2—2 of Figure 1;

Figure 3 is a central vertical section through a modified form;

Figure 4 is a horizontal section taken on the line 4—4 of Figure 3;

Figure 5 is a fragmentary central vertical section through another modified form;

Figure 6 is a horizontal section taken on the line 6—6 of Figure 5;

Figure 7 is a central vertical section taken through a fourth modified form;

Figure 8 is a plan view of the container of the form of Figure 7 with the closure removed;

Figure 9 is a fragmentary central vertical section through a fifth modified form;

Figure 10 is a detail cross section taken on the line 10—10 of Figure 9;

Figure 11 is a detail perspective view showing the insert used in the form of Figures 7 to 10;

Figure 12 is a central vertical sectional view through another modified form;

Figure 13 is a cross section taken on the line 13—13 of Figure 12;

Figure 14 is a horizontal section taken on the line 14—14 of Figure 12;

Figure 15 is a perspective view of the insert used in the form of Figures 12 to 14; and

2

Figure 16 is a fragmentary view partly in elevation and partly in section showing an insert of the general character of that of Figure 15 held in place by a bayonet joint.

Referring specifically to the drawings wherein like reference characters designate like or similar parts and first to the form of Figures 1 to 2, 10 designates a suitable container or receptacle which may be of any desired size and shape and material, for instance, being of glass or plastic. At either end, container 10 has a closure 11 that is screw threaded thereto or otherwise detachable as at 12. Closure 11 may be of any suitable material, for instance, metal or plastic.

15 Formed integral with the container 10 or separately applicable thereto as preferred is a wall or tube 12 depending from the top of the container and terminating short of the bottom of the latter and at the top of the container, a pouring or dispensing spout 13 may be provided in line with the passage 14 or bore of the tube 12.

15 Formed integral with the container 10 or separately applicable thereto as preferred is a wall or tube 12 depending from the top of the container and terminating short of the bottom of the latter and at the top of the container, a pouring or dispensing spout 13 may be provided in line with the passage 14 or bore of the tube 12.

A removable measuring device 15 which may be of metal, plastic or otherwise, has two tubular extensions 16 and 17 whose bores are connected by a passage at 18. The tube 16 is removably inserted into the bore or passage 14 and will remain therein by friction and will also be held in place since it rests on the closure 11.

It will be seen that in using the structure of Figures 1 and 2, a predetermined or measured quantity of sugar or other material will enter the measuring device 15 through the tube 17 and will be dispensed from said device when tilted, discharging through the spout 13. After a dispensing operation, and the closure 11 again rests on a table in horizontal position, a succeeding predetermined or measured quantity of sugar or other material will enter the measuring device 15, so as to be dispensed upon the next tilting movement of the container.

It is clear that various forms may be provided to carry out the principles of my invention. In the second form of Figures 3 and 4, a container 10' is provided of the same material as the container 10 and equipped with a similar screwed-on metal closure 11'. Formed integral with the side wall of container 10' are spaced apart ribs 19. Slidably mounted by the ribs 19, so that it may be removed, is a half-tube 20 which may be of metal or plastic material, such tube 20 and ribs 19 preferably having overlapping flanges as at 21 and 22, respectively. Welded or otherwise secured or even formed integral with the tube 20 is a measurer 23. This element may be of any desired shape, or of the same material as the tube

20, the same being bowed outwardly with respect thereto so as to form an entrance opening at 24. It will be noted that the measurer 23 extends below the tube 20 so that the material such as sugar, may extend across the lower end of the latter and be discharged through the tube 20 and an opening 25 in the container 10', when the latter is tilted. The tube 20 and part 23 are removed and replaced as a unit, being frictionally held in place and also being held in place by the closure 11' upon which the measurer 23 rests. The latter may have an outwardly-extending lug 25 to form a means for engagement by the finger-nail in removing the unit 20—23.

In the modified form of Figures 5 and 6, the parts 10a and 11b correspond to those at 10 and 11, and the former has a tube 12a therein like that at 12, but preferably extending a little closer to the closure. In this form I provide a measurer 15a separate from the closure 11b and the tube 12a. Such measurer has a bowed portion 17a outwardly of the tube and has terminal fingers or grips 16a. Measurer 15a is preferably made of spring metal, plastic or the like, and the fingers 16a function as clasp fingers to grip the lower portion of the tube to maintain the measurer in place. It is also held in place against lowering movement since it rests on the closure 11b. In dispensing with this form of the invention, it will be realized that the material enters through the open top of the bowed portion 17a, thence beneath the tube 12a and out of the tube, upon properly tilting the container 10a.

Referring now to the form of Figures 7, 8 and 11, a container 10b corresponds to that employed at 10, having a closure 11b detachably screwed thereto as at 12b, the closure in this instance being at the top, for example, rather than at the bottom as in the preceding forms. Container 10b has an integral wall 25 shown as providing a dispensing receptacle 26 of oval shape in cross section, although it may be round if desired. To complete the measuring feature, I employ a metallic or plastic insert 27 as detailed in the perspective of Figure 11. This insert is positioned in the receptacle 26 from above and the periphery of the bottom 28 of the insert frictionally engages the adjacent walls to hold the insert in place. To attain this end, the inner surface of the receptacle 26 at wall 25 may be slightly tapered in a downward direction. Also, optionally, I may provide lugs 29 at the top of a partition 30 rising from the bottom 28 and which lugs 29 are disposed or suspended in notches 31 provided in the upper edge of the container 10b. When the closure 11b is in place, it will hold the insert 27 against displacement, also, and it closes the top of the receptacle 26 except for an inlet opening 32 in the wall 25. An opening 33 is provided in the partition 30 and an outlet opening 34 is provided in the closure 11b. As a result, a predetermined or measured quantity of sugar or other commodity, at an angle of tilt, will enter the measuring receptacle through the opening 32, and at another of tilt will be dispensed or poured therefrom by way of the openings 33 and 34.

In Figures 9 and 10, the structure is substantially the same as in Figures 7 and 8, except I use a receptacle or measurer-forming wall 35 of metal, plastic or the like, which may be cast in place permanently in the container 10c, the equivalent of that at 10b, or be removably slideable since it has ribs 36 engaging behind ribs 37 of the container. It will be clear that I may omit the wall of the measurer 35 which is in con-

tact with the side wall of the receptacle 10c, if desired. In this form, I also use the insert 27 as employed in Figures 7 and 8, the wall 35 preferably tapering slightly so that its smaller dimension is lowermost to increase the frictional engagement of the bottom 28 therewith. The wall 32' corresponds to that at 32 and to facilitate entry of sugar or other commodity into the measurer 35, the plate or plastic closure employed at 11c is upwardly bulged as at 38. The material will be dispensed with the same action as in Figure 7 and a pouring spout 39 is provided on the closure 11c in line with the left-hand half of the measuring receptacle.

The form of Figure 12 has a container 10d like that at 10 provided with a metallic or plastic closure 11d screwed in place thereon at 40. A measuring receptacle in the form of a tube 41, of any desired cross-sectional configuration, is fastened to and suspended from the closure 11d as at 42. The tube 41 may be central or eccentric as shown, as preferred. An insert 43, as detailed in Figure 15 is removably applicable to the tube through its lower end. This insert has a partition wall 44 and the insert is preferably made of flexible metal or plastic so that the insert may be initially slightly curved or deflected out of a plane as suggested by the dotted lines in Figure 15, to the end that the partition will be moved into such plane and so held through its engagement with the interior of the tube, as the width of the partition corresponds to the diameter of the tube. Partition 44 is fastened to a bottom element 45 which abuts the tube 41 and the partition at its bottom has an opening 46 therethrough. At the top, the partition has a lateral wall at 47, which is optional, and below the wall 47, the tube 41 has an entrance opening 48. The latter opening may be at the top of the tube, however, if desired. It will also be noted that a pouring or discharge opening 49 is provided in the closure 11d in registry with the tube 41 at the left of the partition 44. Thus, the sugar or other material will be dispensed through the proper movements, the sugar entering the opening 48, passing through opening 46 and thence out of the tube 41 through the opening 49.

In the modified form of Figure 16, a measurer or tube 41a corresponds to the tube 41, and an insert 43a corresponds to that at 43, having a similarly functioning partition 44a and bottom 45a. The bottom extends into the tube, in contrast with the form of Figures 12 to 15, and one or more pins 50 are provided on the periphery of the bottom 45a so as to engage with a corresponding bayonet slot or slots 51 in the tube 41a.

It will be seen that in all of the forms of the invention, that the sugar or any other commodity will be dispensed in a predetermined or measured quantity and without waste, and that one or more of the parts are removable so that all of the parts may be maintained clean and sanitary, and further that the various forms may be expeditiously made, since they are simple and inexpensive. They avoid corners, projections or collecting places for unsanitary accumulations and deposits.

Various changes may be resorted to provided they fall within the spirit and scope of the invention.

I claim as my invention:

1. In combination, a container having a dispensing opening, a wall integral with the main wall of the container removable means in the container and positioned by said walls and coacting

with the latter to measure and dispense the contents through successive angular manipulation thereof, said removable means including a bottom for said measuring chamber, and a closure for the container bearing against said means and aiding in maintaining it in place.

2. In combination, a container having a dispensing opening, a wall integral with the main wall of the container removable means in the container and positioned by said walls and co-acting with the latter to measure and dispense the contents through successive angular manipulation thereof, said removable means including a bottom for said measuring chamber, a closure for the container bearing against said means and aiding in maintaining it in place, said closure partly closing said means so that the latter will operatively function.

3. In combination, a container, means within the container forming a longitudinally extending measuring chamber, an insert positioned in the chamber and carrying a bottom therefor, said means and insert having laterally disaligned openings and the container having a pouring opening in communication with the chamber, whereby the contents of the container may be dispensed through successive tiltings.

4. In combination, a container, means within the container forming a longitudinally extending measuring chamber, an insert positioned in the chamber and carrying a bottom therefor, said means and insert having laterally disaligned openings and the container having a pouring opening in communication with the chamber, whereby the contents of the container may be dispensed through successive tiltings, the said means being a wall integral with the container.

5. In combination, a container, means within the container forming a longitudinally extending measuring chamber, an insert positioned in the chamber and carrying a bottom therefor, said means and insert having laterally disaligned openings and the container having a pouring opening in communication with the chamber, whereby the contents of the container may be dispensed through successive tiltings, the said means being a wall secured to the container.

6. In combination, a container, means within the container forming a measurer, an insert positioned in the measurer, said measurer and insert having disaligned openings and the container having a pouring opening in communication with the measurer, whereby the contents of the container may be dispensed through successive tiltings, said insert having a bottom wall and a partition through which the aforesaid opening of the insert is provided adjacent the bottom wall.

7. In combination, a container, means within the container forming a measurer, an insert positioned in the measurer, said measurer and insert having disaligned openings and the container having a pouring opening in communication with the measurer, whereby the contents of the container may be dispensed through successive tiltings, said insert having a bottom wall and a partition through which the aforesaid opening of the insert is provided adjacent the bottom wall, lugs at the top of the partition and the container having notches engaged by the lugs to suspend the insert.

8. In combination, a container, means within the container forming a measurer, an insert positioned in the measurer, said measurer and insert having disaligned openings and the container having a pouring opening in communication with

the measurer, whereby the contents of the container may be dispensed through successive tiltings, said insert having a bottom wall and a partition through which the aforesaid opening of

5 the insert is provided adjacent the bottom wall, lugs at the top of the partition and the container having notches engaged by the lugs to suspend the insert, said container wall being tapered with the smaller dimension lowermost to enable said

10 bottom of the insert to frictionally wedge in place.

9. In combination, a container, a closure applicable thereto, a tube depending from said closure having an opening for the inlet of material from the container, an insert comprising a partition insertable in the tube and a bottom from which the partition extends, said bottom also functioning as the bottom of the tube, said partition having an opening therethrough adjacent the bottom, and the closure having an opening therethrough at the side of the partition opposite to the first-mentioned opening.

10. In combination, a container, a closure applicable thereto, a tube depending from said closure having an opening for the inlet of material from the container, an insert comprising a partition insertable in the tube and a bottom from which the partition extends, said bottom also functioning as the bottom of the tube, said partition having an opening therethrough adjacent the bottom, and the closure having an opening therethrough at the side of the partition opposite to the first-mentioned opening, said partition being deflected from a plane, whereby it will be rendered planar by engagement with the tube so that it will be frictionally held in place in the latter.

11. In combination, a container, a closure applicable thereto, a tube depending from said closure having an opening for the inlet of material from the container, an insert comprising a partition insertable in the tube and a bottom from which the partition extends, said bottom also functioning as the bottom of the tube, said partition having an opening therethrough adjacent the bottom, and the closure having an opening therethrough at the side of the partition opposite to the first-mentioned opening, said partition being deflected from a plane, whereby it will be rendered planar by engagement with the tube so that it will be frictionally held in place in the latter, and a wall at the upper end of the partition extending away from the third-mentioned opening.

12. In combination, a container, a closure applicable thereto, a tube depending from said closure having an opening for the inlet of material from the container, an insert comprising a partition insertable in the tube and a bottom from which the partition extends, said bottom also functioning as the bottom of the tube, said partition having an opening therethrough adjacent the bottom, and the closure having an opening therethrough at the side of the partition opposite to the first-mentioned opening, and a bayonet slot connection between the insert and tube.

13. In combination, a container having a cover provided with a dispensing opening, means on the container providing a longitudinally extending measuring chamber, and removable means co-acting with the first-mentioned means disposed in the said chamber separate from the cover suspended on the container to measure and dispense the contents through successive angular manipulations thereof, said removable means including 70 a bottom for said measuring chamber.

14. In combination, a container member, a removable closure member therefor, one of the members having a tube enclosed by the members, said closure member having an opening communicating with the tube, a longitudinal partition removably interengaged with the tube and including a bottom for said tube, said partition having an opening therethrough adjacent said bottom and the tube on the side of the partition opposite to the first-mentioned opening having an opening disaligned with that of the partition.

15. In combination, a container member, a removable closure member therefor, one of the members having a tube enclosed by the members, said closure member having an opening communicating with the tube, a longitudinal partition removably disposed within the tube including a bottom for the tube, said partition having laterally projecting means, and said container member in its upper edge being recessed and receiving said projecting means below said upper edge and the tube on the side of the partition opposite to the first-mentioned opening having an opening disaligned with that of the partition.

16. In combination, a container member, a removable closure member therefor, one of the members having a tube enclosed by the mem-

bers, said closure member having an opening communicating with the tube, the interior wall of said tube being transversely curved, a longitudinal partition removably disposed in the tube, said partition being initially bowed and of a width to co-act with the curvature of the tube to maintain the partition straight and interengaged with the tube, said partition including a bottom for said tube, said partition having an opening therethrough adjacent said bottom and the tube on the side of the partition opposed to the first-mentioned opening having an opening disaligned with that of the partition.
